UNITED STATES PATENT OFFICE.

ROYAL RUEBEN MILLER, OF PUEBLO, COLORADO.

ADJUSTABLE INVALID-COT.

982,289.

Specification of Letters Patent. Patented Jan. 24, 1911.

Application filed March 16, 1910. Serial No. 549,709.

To all whom it may concern

Be it known that I, ROYAL RUEBEN MILLER, a citizen of the United States, residing at Pueblo, Colorado, have invented certain new and useful Improvements in Adjustable Invalid-Cots, of which the following is a specification.

My invention relates to improvements in adjustable cots in which a cot is elevated above the mattress on the bed by pulley and screw means.

The objects of my invention are, to provide an adjustable cot attachable to bedsteads, to provide means for adjusting the fabric beneath the patient, to simplify the means of construction of an adjustable cot, to provide means of elevating such cot by screw means and to provide a method for attaching the fabric to the sides of the cot. I attain these objects by the mechanisms illustrated in the accompanying drawings, in which,—

Figure 1 is a side elevation showing my device attached to a bed; Fig. 2 is a broken section in plan view showing means for attaching the edges of the fabric to the sides of the cot frame; Fig. 3 is a perpendicular sectional view showing the tube containing the screw threaded means of operating the cables over pulleys; Fig. 4 is a perpendicular cross sectional view of the tubing containing the pulley means in which operates one of the elevating cables; Fig. 5 is a plan view in broken section of the cot showing the attachment of cables and means of tightening the fabric; Fig. 6 is a broken sectional side view showing the ratchet and pawl on the end of the cot for holding the fabric tight; and Fig. 7 is a perspective view in broken section of one of the sides of the cot showing the fabric and means of attaching the same to the sides of the cot frame.

Similar numerals refer to similar parts throughout the several drawings.

On the ends 1 of a bed is attached, preferably the foot of the bed, the square tubing 3, by clamp and hook means 4 and 5. On the other end 1 of the bed, preferably the head, is attached the tubing 14 by clamp means 15. Fixed on the upper end of the square tubing 3 is the pulley head and bearing 6 in which is adjusted the pulley 8. In the top of bearing 6 a space 6^a is provided for a threaded bar 22 to pass through. At the bottom of the square tubing 3 is at-

tached the pulley and bearing head 7 in which is adjusted the pulley 9. A screw threaded bar 22, the upper part 22^b being right threaded and the lower part 22^a being left threaded, the threaded parts being preferably of equal length, is adjusted on the interior of the square tube 3, in suitable bearings at each end of said tube. On the interior of the square tube 3 engaging the threads 22^b is the threaded nut 26 to which is attached the cable 10. Also in the interior of said square tube 3, engaging the threads 22^a is the threaded nut 27, to which is attached the cable 21. These threaded nuts 27 and 26 are preferably made square so as to prevent turning. If desired, these nuts may be provided with anti-friction bearings against the inside of the tube. In the bottom of the bearing 7 the space 7^a is provided for the end portion of the threaded bar 22. There is attached at the bottom of the threaded portion 22^a a thrust collar 23 held in position by cotter pin means 23^a. On the upper portion 22^b of the threaded bar a thrust collar 24 is fixed and held in position by cotter pin means 24^a. The upper portion of the threaded bar extends through the opening 6^a and has a square head 25 to which may be applied the crank 20. It is apparent that the parts of the bar 22 may be threaded opposite to the way indicated.

The cot frame is composed of the round side bars 28, preferably hollow, divided at 39 and adjustable with a piece sliding into the interior of each bar 28 fixed by set screw means 40. To each end piece 30 is attached the pawl 31. In one end of each side piece 28 is a ratchet wheel 29 in which the pawl 31 engages and adjacent thereto in the side bar are the holes 32 for applying the bar 33. Each side bar 28 is turnable in the end bars 30 by having a shoulder fitting a bearing in each end of each end bar and is held by screw and nut means 38. On each side bar 28 a metal strip 37 is attached with an extending flange parallel with the surface of the side bar 28 but leaving a required space. On the edge of each side of the fabric 34 a pocket 35 is prepared into which fits the strip 36. The strip 36 is placed in the pocket 35, and the pocket is placed in the flange portion of 37 and the flange is so placed that the pull of the fabric is against the free edge of the flange 37 on each side bar when a side bar is turned to tighten the

fabric. The cables 12 are attached to each end piece 30, one to each end of each end piece and united at 11 to the cables 10 and 21 respectively.

5 The crank 20 is provided, fitting the square head 25. The tubing 14 attached as above stated to the end of the bed opposite to the square tubing 3 has attached to it the pulley head 18 in which is adjusted 10 the pulley 19, and the pulley head 16 in which is adjusted the pulley 17. The side bars 28 by means of the divisions at 39, when the device is not in use, may occupy a lesser length, and by means of the set screws 40 on 15 an interior bearing piece may be made the required length for use.

The cot is placed over the ordinary mattress 2 and the fabric adjusted to the required tension by turning the side bars 28 20 with the lever 33, and the ratchets 29 and pawls 31 hold the fabric at the required tension. The cables being attached to the cot and over the respective pulleys, and the patient having been placed on the cot, the operator, by applying the crank 20, may elevate 25 the cot to the desired position and the cot will stay in that position until the operator turns the crank 20 in the opposite direction and lets the cot down to the mattress 2. 30 Means for attaching the cables at 11 by any well known hook means or at 13 may be provided and either end of the cot be detached from connection with the cables and the opposite end may be elevated, or in like manner either side may be elevated and the device may be used in connection with leaves on the cot so that one part may be elevated 35 and the other part remain stationary.

In this device it readily appears that a 40 modification of the form of attachment of the cables to the cot frame, or a modification of the cot frame, or a modification of the pulley means, could be made without departing from the principle of my invention, in simplicity and novel means of elevating the cot frame, and in attaching the edges of the fabric to the sides of the cot.

I am aware that invalid cots in which the cot may be elevated have been constructed 50 and I do not claim broadly the elevation of the cot as my invention.

I claim:

1. In an invalid cot attachable by clamp means to a bedstead having a cot frame attached by cable means to two operating

cables, fabric covering said frame, tubing adapted to contain one of the operating cables with pulleys on said tubing one at each end to carry one of said operating cables, the combination of tubing provided 60 with pulley and bearing means at each end adapted to carry both of said operating cables, threaded nuts slideable in and not turnable in last said tubing to each of which nuts is attached one of said operating cables, 65 a crank, and a threaded bar turnable on bearings in said tubing one part threaded right hand and the other part threaded left hand, adapted to engage said nuts and provided with a head adapted for engagement 70 of said crank, all substantially as described.

2. In an invalid cot provided with two upright tubing pieces each carrying a pulley at each end, one tubing piece adapted to permit the passing of a cable through it, both 75 attachable by clamp means to the ends of a bedstead, having operating cables suitably disposed over said pulleys, also provided with a cot frame attachable by cable means to said operating cables and including suitable operating crank means, the combination of a right handed threaded nut and a left handed threaded nut to each of which is attached respectively one end of one of said operating cables, disposed within one of said tubing pieces and not turnable therein, and a bar on bearings within last said tubing piece one part threaded right hand with the other part threaded left hand adapted to engage said nuts having a head adapted to 80 engagement with said crank means, all substantially as set forth.

3. In an invalid cot of the character described, an upright tubed piece adapted to carry nuts slideable and not turnable therein 95 and provided with end bearings carrying pulleys; two threaded nuts disposed in said tubed piece each adapted to have attached thereto cable means adapted to elevate and lower simultaneously both ends of a cot; a 100 threaded bar, one part threaded in one direction the other threaded in the other direction, adjusted turnably in said end bearings of said tubed piece and adapted to engage said nuts, all substantially as set forth. 105
